DROP SEAT GARMENT

Ruth A. Moeller, Miami, Fla.

Application June 22, 1950, Serial No. 169,631

2 Claims. (Cl. 2-79)

1

This invention relates to a drop seat garment and, more especially, to an improvement in one-piece slack suit apparel.

The apparel to which the invention may be particularly applied has utility as a slack suit for women's wear, coveralls, work clothes and the like, but is not limited within the scope of my invention to a garment intended for any specific use or purpose.

An object of the invention is to provide a drop seat garment of the character described which will be simple in construction and convenient and serviceable in wearing characteristics.

Another object is to provide a drop seat garment in which the seat construction is substantially concealed.

A further object is to provide a garment of the character described which is pleasing in appearance and readily adapted to fit comfortably and snugly about the person of the wearer.

Other advantages of the invention will be discernible from the detailed description thereof hereinafter set forth.

According to the invention, the garment comprises an upper or jacket portion and a lower trousers portion formed therebelow, a drop seat panel formed out of the trousers portion and a belt defining the top marginal edge thereof, and a pair of pockets foldable from a corresponding pair of pocket panels extending from the lower region of the jacket portion. By this construction, the pockets provide a continuous extension of the jacket portion which underlies the trousers portion whereby to afford concealment of the wearer's torso at the junction of the drop seat marginal sides and the trousers portion adjacent thereto when the belt is encircled about the waist of the wearer in secured position. A further unique characteristic of this arrangement is that the end portions of the belt form one notch with the marginal sides of the drop seat attached thereto and the pocket entrance members form an opposite complementary notch with the jacket portion thereabove whereby, when these opposed notches are brought together upon the encirclement of the belt about the wearer's waist, a neat and positive closure of the meeting parts is readily effected to provide a snugly fitting garment of pleasing appearance.

The invention is embodied in the garment exemplified by the accompanying drawings in which the views are as follows, like reference numerals designating similar parts throughout the several views:

Figs. 1 and 2 are perspectives of the garment as conventionally worn;

Fig. 3, a typical panel out of the rear part of the jacket portion emphasizing the pocket panels extending therefrom;

Fig. 4, a rear trousers panel;

Fig. 5, a frontal trousers panel;

Fig. 6, the assembly of views shown in Figs. 4 and 5;

Fig. 7, a fragmentary detail of the pocket panels in relation to the trousers portion incorporated therewith.

The drop seat garment is depicted in the drawings as having an upper or jacket portion 1 (Figs. 1 and 2), with which is associated the trousers portion 2, the frontal part of the jacket portion being formed out of a panel 3 which is the upper region of the trousers panel (Fig. 5), the panel 3 being united in assembly with the back panel 4 of the jacket portion shown in Fig. 3. The suit may have an opening 5 fastened by zipper or buttoning. The jacket may have sleeves 6, the trousers portion having the usual leg extensions 7 which, at their upper regions unite, preferably integrally, with the front panels 3 of the jacket portion. In the back thereof, the jacket portion terminates in a short tail or skirt 8, to which a slight flair may be imparted by a suitable gathering-in 9 incorporated in the waist region.

A drop seat 10 (Fig. 2) is defined in the upper region of the trousers portion, occurring above the broken line 10A. Attached to the drop seat along the top edge thereof, is a belt 11 adapted to encircle the wearer in the waist portion to secure the garment in closed position.

Extending from the jacket panels (Fig. 3), is a pair of pocket panels 12, foldable along fold lines 13 and united, after folding, along the angular seam lines 14. The outer edges of these pocket panels define a triangular tab 15 adapted to unite with a complementary tab 16 after sewing along seam line 17, these tabs occurring in the hip region at the sides of the garment.

When worn in secured position with the belt encircling the waist, a notch 19 formed by the junction of tab 16 with the jacket portion thereabove is engaged with a complementary notch 20 formed by the junction of the end portions of the belt with the side marginal edges 21 of the drop seat (Fig. 4), thereby providing a neat and positive interlocking closure between the pocket entrance members and the opposite trousers portion brought thereagainst when the drop seat is secured in wearing position. The gathering-in structure 9 tends to draw the flaps formed by tabs 15 and 16 rearwardly about the hips.

Thus, when the belt is drawn about the waist of the wearer, thereby moving the drop seat mar-

ginal sides 21 forwardly in respect to the hips, the gathering-in structure 9 tends to retract the flaps of the pockets in the opposite direction to bring notches 19 and 20 into close interlocking engagement to assure the wearer a snug fitting and trim appearing garment. Further, by virtue of the construction of the pocket members, the sacks thereof hang independently in a practical sense, of the trouser leg parts; thus, when the wearer thrusts the hands into the pockets, the back region of the garment is brought into a snug fitting relation over the torso, the thrust thus applied pulling the jacket portion thereover.

I may employ the usual dart construction, as at 22, to impart comfort and style to the garment.

My invention is thus seen to provide a drop seat garment construction of unique characteristics, which is simple and efficient in the practice thereof, affording the wearer a maximum degree of convenience and comfort, especially in getting into and out of the garment.

While the drawings depict panels in views showing partial delineations of the various panels making up the garment, it will be understood that these illustrations suggest symmetrical arrangements which will be readily comprehended by those skilled in the art.

I do not limit the application of the invention to a particular style, the teachings thereof being alike relevant to sun suits, play suits, bathing suits, or any suitable apparel fabricated, in preference, in a one piece suit, without any specific arrangement of the seams.

Of course, the invention is susceptible of a variety of modifications and changes in design without, however, departing from the spirit and scope of the invention as hereinafter claimed.

I claim:

1. In a drop seat garment, the combination of a front jacket panel and a front trouser panel with the rear edges thereof adjacent the waistline junction between said panels converging to form a notch at said junction, a rear jacket

panel terminating at its lower edge in a skirt portion having a forwardly extending portion constituting a pair of pocket forming members adapted to underlie said front trouser panel, the edges defining said notch providing an entrance to said pocket when said pocket forming members underlie said front trouser panel, and a rear trouser panel adapted to overlie the skirt portion of said rear jacket panel and having a belt attached along the upper edge thereof with a free end of said belt extending beyond the front edge of said rear trouser panel, said rear trouser panel having a flap at its forward edge and below said belt with the forward edge of said flap and the lower edge of the free end of said belt defining a notch therebetween, said front and rear trouser panels having their respective rear and front edges secured together from their lower ends upwardly to a point spaced below said flap and belt with the unsecured edges providing a drop seat portion at the upper portion of said rear trouser panel, said belt adapted to encircle the waistline junction between said jacket and trouser panels and to maintain said flap in position beneath the front trouser panel with the said notches in engagement, the overlying position of said front trouser panel with respect to said flap forming a side closure.

2. A drop seat garment as defined in claim 1 in which the rear jacket panel has a gathering in structure at the back thereof at the top of the skirt portion of said panel.

RUTH A. MOELLER.
